(57) **CLAIM**

The ornamental design for a circular arc handle, as shown and described.

DESCRIPTION

FIG. 1 is a front elevational view of a circular arc handle showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view thereof;

FIG. 8 is a reduced environmental perspective view;

FIG. 9 is a second reduced environmental perspective view; and,

FIG. 10 is a third environmental perspective view.

The broken line structures that are shown in FIGS. 8-10 are for illustrative purposes only and form no part of the claimed design.
